CLAIM

The ornamental design for a tyre tread as shown and described.

DESCRIPTION

1. Tyre tread

1.1 : Perspective

1.2 : Front

1.3 : Left

1.4 : Enlarged

1.5 : Enlarged

1.6 : Cross sectional

1.7 : Cross sectional

Fig.1.3 is a left view of the tyre tread, the right view being identical; Fig.1.4 is a fragmentary enlarged perspective view surrounded by line 4-4 and line 4'-4' in Fig. 1.1; Fig.1.5 is a fragmentary enlarged front view surrounded by line 5-5 and line 5'-5' in Fig.1.2; Fig.1.6 is a cross-section view taken along line 6-6 in Fig.1.5; Fig.1.7 is a cross-section view taken along line 7-7 in Fig. 1.5; In the drawings, the pattern repeats uniformly throughout the circumference of the tyre tread, and broken lines depict environmental subject matter only and form no part of the claimed design.
